UNITED STATES PATENT OFFICE.

JOSEPH TRAFFORD, OF BOSTON, MASSACHUSETTS.

CHAMPAGNE-FREEZER.

SPECIFICATION forming part of Letters Patent No. 714,415, dated November 25, 1902.

Application filed February 12, 1902. Serial No. 93,747. (No model.)

To all whom it may concern:

Be it known that I, JOSEPH TRAFFORD, a subject of King Edward VII, residing at Boston, in the county of Suffolk and State of Massachusetts, have invented new and useful Improvements in Champagne-Freezers, of which the following is a specification.

The object of this invention is to provide a cooler for champagne, wine, or other beverages, and particularly a cooler in which a number of bottles may be placed and rotated at one time and which shall be strong, durable, convenient, and easily and quickly operated.

15 The invention consists, in a champagne-freezer, of an ice-cooler, a gear-frame pivoted thereto, a clamp to lock said gear-frame to said ice-cooler, a main vertical rotary shaft journaled in said gear-frame, a main spur-gear fast to said shaft, a series of vertical shafts journaled in said gear-frame and concentric with said main vertical shaft, a pinion spur-gear fast to each of said vertical shafts and meshing into said main spur-gear, 25 and a bottle-clamp fast to the lower end of each of said vertical shafts.

20 The invention again consists in specific means for clamping the gear-frame to the ice-cooler.

30 The invention again consists in the specific form of clamp by means of which the bottle is connected to and rotated by said vertical shafts, said clamp consisting of two parts, one of said parts formed to partially encircle 35 the neck of a bottle and the other part being pivoted thereto upon a horizontal pivot and adapted to engage the neck of a bottle and clamp the same against said first-named part.

30 The invention finally consists in the combination and arrangement of parts set forth in the following specification, and particularly pointed out in the claims thereof.

Referring to the drawings, Figure 1 is a central vertical section, partly in elevation, 45 of my improved champagne-freezer. Fig. 2 is a plan view of the gear-frame with the gears thereon. Fig. 3 is a detail section of the bottle-clamp, taken on line 3 3 of Fig. 1. Fig. 4 is an enlarged side elevation, taken 50 from the left of Fig. 1, of the end of the gear-frame, together with the clamp - lever by

which said gear-frame is locked to the ice-cooler. Fig. 5 is a plan view of a champagne-freezer constructed in accordance with my invention adapted to contain six bottles at one time. Fig. 6 is a vertical section, partly in elevation, taken on line 6 6 of Fig. 5.

Like numerals refer to like parts throughout the several views of the drawings.

In the drawings, 10 is an ice-cooler divided 60 into an upper compartment 11 and a lower compartment 12 by a perforated partition 13. A gear-frame 14 is pivoted at 15 to a bracket 16, fast to the inner face of rim of the ice-cooler 10. Said gear-frame has two downwardly-depending ears 17 17, Figs. 1 and 4, at the left-hand end thereof. Each of the ears 17 is provided with a vertical slot 18, through which a clamp-bolt 19 projects, said clamp-bolt being fast to said cooler 10 and provided with a clamp-handle 20, pivoted thereon. By means of the clamp-handles 20, and clamp-bolts 19 the gear-frame 14 is held firmly locked to the ice-cooler 10, as is shown in Fig. 1.

75 The gear-frame 14 is provided with two vertical rotatory shafts 21, journaled therein, each of said shafts having a bevel-gear 22 fast to the upper end thereof, and each of said bevel-gears 22 meshing into a bevel-gear 23, fast to a horizontal shaft 24, journaled in bearings 25 25, projecting upwardly from the gear-frame 14. The horizontal shaft 24 is rotated by means of a handle 44. The vertical shafts 21 project downwardly below the gear-frame 14, and each shaft has attached thereto a clamp 30, formed in two parts. One of said parts 26 is fast to the lower end of the vertical shaft 21 by a cross-pin 27. The other of said parts 28 is pivoted to a horizontal screw 29, fast to the part 26, and projects downwardly from said screw, as shown in Fig. 1.

90 The bottles 31 31, filled with the wine which it is desired to chill, are clamped at the upper ends thereof by the clamps 30, the lower end 95 of each bottle being, as is usual in bottles of this class, provided with a recess 32. Said recess receives a centering-support 33, which is fast to the upper surface of the perforated partition 13 and projects downwardly therefrom into said recess 32. The center of the centering-support 33 is in line with the cen-

ter of the rotatory shaft 21, so that as the bottle is rotated, as hereinafter described, the two ends thereof will be held in line.

As seen in Fig. 3, the part 26 of the clamp 30 partially encircles the upper end or neck of the bottle 31, while the part 28 clamps and holds said bottle against said part 26. The upper compartment 11 is filled to any desired height with ice 34, and as said ice melts the 10 water flows through the perforated partition into the lower compartment 12 and is drawn out of said lower compartment by a waste-cock 35.

The general operation of my improved 15 champagne-cooler, as illustrated in Figs. 1, 2, 3, and 4, is as follows: The bottles 31 are placed in position upon the centering-supports 33. The gear-frame 14 is turned upon the pivot 15 and brought down to the horizontal 20 position (shown in Fig. 1) and clamped in position by means of the clamp-bolts and handles 19 and 20, respectively, this operation bringing the part 26 of the clamp 30 into contact with one side of the neck of the bottle 31. The second part 28 of said clamp 30 is then brought down into the position shown in Fig. 1, thus firmly holding the neck of the bottle in position against the part 26, as shown in Figs. 1 and 3. The ice having been packed in 25 the cooler, as shown in Fig. 1, the shaft 24 is rotated by means of the handle 44, thus imparting a rotary movement to the gears 23 and 22, the vertical shafts 21, the clamps 30, and the bottles 31, held by said clamps. When 30 the wine in the bottles has been sufficiently chilled, the clamp-handles 20 are thrown upwardly, disengaging the bottle from the clamp 30. The clamp-handle 20 is released to allow the gear-frame 14 to be raised. Said gear-frame is tipped upon its pivot 15, and thus 35 the bottles are entirely uncovered and easily removed from the ice-cooler, as well as the ice which is contained in said ice-cooler, if it is desired to remove the same. It will be seen that the bottles are firmly held during 40 this operation by the clamps 30 and by the centering-supports 33. It will also be seen that the machine is easily operated and that the gear-frame by its construction and arrangement can be entirely disconnected and 45 thrown over to leave the interior of the ice-cooler open at the top and easy of access.

In Figs. 1 to 4, inclusive, I have shown my invention adapted to a freezer containing 50 only two bottles; but the same may be increased to any desired number of bottles by arranging the bottle-clamps in connection with gearing, as shown in Figs. 5 and 6, in which the ice-cooler, bottle-centering support, 55 and bottle-clamps are substantially the same as in the form hereinbefore described; but the clamps 30 are six in number, and the vertical shafts 21 each have a spur-gear 36 fast to the upper end thereof, meshing into a spur-gear 37, fast to a main vertical rotary shaft 38, to the lower end of which is attached one of the bottle-clamps 30 and to the upper end of

which is fastened a bevel-gear 39. The bevel-gear 39 meshes into a bevel-gear 40, fast to a horizontal shaft 41, which is journaled in 70 bearings 42 upon the upper surface of the gear-frame 43. In this form of my invention the shaft 41 is rotated by means of a handle, thus imparting rotary movement to the bevel-gear 40, bevel-gear 39, main spur-gear 37, 75 and, through the spur-gear 37, to the pinion spur-gears 36, each of which being fast to a vertical shaft 21, concentric with the main vertical shaft 38, rotates the clamps 30 on the bottles 31, fast to said clamps. The gear-frame 43 is clamped to the ice-cooler in this form as in the form hereinbefore described, and the operation of tipping the said gear-frame backwardly upon its pivot to obtain free access to the interior of the cooler is the 85 same as in the form hereinbefore referred to.

Having thus described my invention, what I claim, and desire by Letters Patent to secure, is—

1. In a champagne-freezer, an ice-cooler, a gear-frame pivoted thereto, a clamp to lock said gear-frame to said ice-cooler, a main vertical rotary shaft journaled in said gear-frame, a main spur-gear fast to said shaft, a series of vertical shafts journaled in said gear-frame and concentric with said main vertical shaft, a pinion spur-gear fast to each of said vertical shafts and meshing into said main spur-gear, and a bottle-clamp fast to the lower end of each of said vertical 90 shafts.

2. In a champagne-freezer, an ice-cooler, a gear-frame pivoted thereto, a clamp to lock said gear-frame to said ice-cooler, a horizontal shaft journaled upon said gear-frame, a bevel pinion-gear fast thereto, a main vertical rotary shaft journaled in said gear-frame, a bevel-gear fast thereto and meshing into said bevel pinion-gear, a main spur-gear fast to said main vertical shaft, a series of vertical 95 shafts journaled in said gear-frame and concentric with said main vertical shaft, a pinion spur-gear fast to each of said vertical shafts and meshing into said main spur-gear, and a bottle-clamp fast to the lower end of each 100 of said vertical shafts.

3. In a champagne-freezer, an ice-cooler, a gear-frame pivoted thereto, a vertical rotatory shaft journaled to said gear-frame, and a bottle-clamp fast to the lower end of said vertical shaft, said bottle-clamp consisting of two parts, one of said parts formed to partially encircle the neck of a bottle and rigidly fastened to said vertical shaft, the other part pivoted to said first-named part and adapted 110 to engage the neck of said bottle and clamp the same against said first-named part.

4. In a champagne-freezer, an ice-cooler, a bracket fast to the inner face of the rim of said cooler, a gear-frame pivoted to said bracket, a downwardly-depending ear upon said gear-frame located inside the rim of said ice-cooler, provided with a vertical slot, a horizontal clamp-bolt fast to said cooler and 115

projecting through said slot, and a clamp-handle pivoted upon said bolt and adapted to engage said ear and clamp said gear-frame to said cooler.

5. In a champagne-freezer, an ice-cooler, a gear-frame pivoted thereto, a clamp to lock said gear-frame to said ice-cooler, a vertical rotary shaft journaled in said gear-frame, a bottle-clamp in two parts, one of said parts
10 formed to partially encircle the neck of a bottle and rigidly fastened to said vertical shaft, a horizontal pivot fast to said first-named

part, the other part pivoted to rotate upon said horizontal pivot and adapted to engage the neck of said bottle and clamp the same 15 against said first-named part.

In testimony whereof I have hereunto set my hand in presence of two subscribing witnesses.

JOSEPH TRAFFORD.
